UNITED STATES PATENT OFFICE.

JOHN BRANDWOOD, OF SOUTHPORT, AND THOMAS BRANDWOOD, OF BURY, ENGLAND, AND JOSEPH BRANDWOOD, OF WABAN, MASSACHUSETTS.

METHOD OF MAKING CONVEYER BANDS.

Application filed June 21, 1924. Serial No. 721,579.

To all whom it may concern:

Be it known that we, JOHN BRANDWOOD, THOMAS BRANDWOOD, and JOSEPH BRANDWOOD, all subjects of the King of Great Britain and Ireland, residing, respectively, at Southport, in the county of Lancaster, England; Bury, in the county of Lancaster, England; and Waban, in the State of Massachusetts, United States of America, have invented a new or Improved Method of Making Conveyer Bands, of which the following is a specification.

These improvements relate to conveyer bands, and more particularly to conveyer bands such as are employed in apparatus wherein materials are held between two endless conveyers to be traversed through an apparatus for the fluid treatment of the material, the fluid passing through the conveyers and through the material in either direction. Although particularly suitable for this type of apparatus the conveyer forming the object of these improvements may however be employed for any purpose for which a conveyer may be employed.

Bands or belts composed of wire spirals threaded into each other, with subsequent flattening of the spirals of the thus woven band, have been proposed, the wire used being of ordinary metal, and the bands employed for the purposes to which bands are usually put and as driving belts. The object of the present improvements is a conveyer band of this type but of non-ferrous metal, ordinary corrodible metal being unsuitable for the special purpose above mentioned. Non-ferrous metals however cannot be formed into a band as described by merely threading the spirals and flattening the whole, as previously proposed, and it is the object of these improvements to provide a band or belt of non-ferrous metals composed of threaded wire spirals flattened to give the necessary conveyer surface. In carrying them into effect we take spirals of a non-ferrous metal, as for instance a nickel alloy, thread or weave them together, wind the so woven band upon a flanged beam or drum, anneal it in that condition, and then pass the band between heavy rollers to flatten the spirals. The longitudinal edges of the band are left free, and we find that as a result of this process each spiral is flattened equally, the said flattening taking place mostly in the length of the woven band when the spi-

rals are transverse to such length. Without annealing, spiral wires of non-ferrous metals will not flatten equally, and the result of any attempt to flatten them is buckling and irregularity of the band surface.

In the drawings annexed, Figures 1 and 2 are respectively plan and end view of a small section of band formed of non-ferrous wire which has been prepared by extrusion in the manner known in the making of mattress wire; Figs. 3 and 4 are similar views of the same section of band after flattening; Fig. 5 is an elevation of one length of wire employed to join the ends of a band together; and Fig. 6 shows the method of making the joint with the jointing length of wire of Fig. 5.

Lengths of wire 7 are prepared as stated above by the method known in the formation of mattress wire, that is to say, the metal is extruded through a rotating die to give the extruded metal its spiral form, the rate of extrusion and rate of rotation of the die regulating the pitch of the spiral. Such method of forming a wire is not of course claimed herein. The lengths of wire 7 are cut to equal lengths, and are threaded or woven into each other as shown in Figs. 1 and 2, these lengths being transverse to the band being formed. The band being completed to the desired length by this means, it is rolled upon a flanged beam or drum, and the said beam or drum is then placed in an annealing furnace. A preferred temperature for the furnace is from 400 to 450 degrees Fahrenheit, this being maintained for about two hours and then allowed to cool down to normal. The beam or drum of wire band is then taken to a roller press, and from the said beam or drum, resting in suitable bearings, the band is fed to the nip of the press rollers and passed between such rollers, the wire spirals being thus flattened evenly. The pressure of the rollers should be about 40 tons to the square inch, but this of course may vary according to the pitch of the spirals and the thickness of the wire.

It is important that the longitudinal edges 8 of the band should be left free to allow for the slight transversal expansion of the wire during the flattening. We find that with the wire spirals woven transversely to the band length the expansion is appreciably greater in the direction of the length of the

band than transversely. With a band of a width of four to five feet and wires of $\frac{1}{16}$ of an inch spiral pitch the transverse expansion will be approximately half an inch.

5 After flattening, the band will present the appearance shown in Figs. 3 and 4, and the longitudinal edges at 8 may be trimmed off by a guillotine or any other convenient implement. In order to form it into an 10 endless band for conveyer purposes, a length of spiral wire 9, Fig. 5, of greater pitch than the wire lengths 7, is taken and threaded through the spirals 7 at the free 15 ends of the band as shown in Fig. 6, where 10 represents one end of the band and 11 the other end.

We find that a band of non-ferrous metal prepared as above described is extremely 20 strong and yet flexible, and it will have the minimum of stretch longitudinally when in use, an important point where a long length 25 of band carrying a considerable weight of metal is required.

Any approved annealing furnace, wind- 25 ing spool or drum, and roller press may be

used in carrying out this invention. It is however important that the spiral wires be woven together and then rolled up into a bundle of convenient size before being annealed, and that all the wires be annealed 30 simultaneously and uniformly before being flattened in the roller press.

What we claim is:

The method of manufacturing a conveyer band intended for the purpose of conveying 35 textile materials through dyeing and analogous liquors, which method consists in weaving together a series of spiral coils of nickel alloy, passing the band thus formed onto a beam on which it is rolled, annealing 40 the band on the beam, passing the said band directly from the beam to pressure rollers, and trimming off the longitudinal ends of the now flattened band.

In testimony whereof we have hereunto 45 set our hands.

JOHN BRANDWOOD.
THOMAS BRANDWOOD.
JOSEPH BRANDWOOD.
